(57) **CLAIM**

The ornamental design for an infant support structure, as shown and described.

DESCRIPTION

FIG. 1 is a front perspective view of an infant support structure according to the present invention; FIG. 2 is a front view of the infant support structure of FIG. 1;

FIG. 3 is a rear view of the infant support structure of FIG. 1;

FIG. 4 is a left side view of the infant support structure of FIG. 1;

FIG. 5 is a right side view of the infant support structure of FIG. 1;

FIG. 6 is a top view of the infant support structure of FIG. 1; and,

FIG. 7 is a bottom view of the infant support structure of FIG. 1.

The broken lines shown in the figures are included for the purpose of illustrating the unclaimed portions of the article and form no part of the claimed design.

1 Claim, 7 Drawing Sheets
